(57) **CLAIM**

The ornamental design for a dumbbell, as shown and described.

DESCRIPTION

FIG. 1 is a front, left and top perspective view of a dumbbell, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of area “9” in FIG. 1.

The broken lines shown in the drawings illustrate portions of the dumbbell that form no part of the claimed design. The dumbbell is shown with a long-short-long dashed symbolic break in its length. The appearance of the break lines and any portion of the dumbbell between the break lines forms no part of the claimed design.
